UNITED STATES PATENT OFFICE.

NELSON M. BAKER, OF SOUTHBRIIDGE, MASSACHUSETTS, ASSIGNOR TO AMERICAN OPTICAL COMPANY, OF SOUTHBRIIDGE, MASSACHUSETTS, A VOLUNTARY ASSOCIATION OF MASSACHUSETTS.

GRINDSTONE.

Application filed November 26, 1923. Serial No. 677,159.

The present invention relates to a floating stone and has particular reference to a stone used in the so-called bevel edging machine wherein accommodation must be made for 5 the various curvatures for the numerous forms of ophthalmic lenses to be ground.

An important object of the invention is to provide a floating stone of this nature wherein in the stone will be free to rock longitudinally of its drive shaft and at the same time 10 to provide driving means that will drive the stone at all times, regardless of its angle to the said drive shaft.

Another object is to provide a floating 15 stone of this nature that is so mounted that it will accommodate itself to any form and curve of lens that is to be ground, being so arranged that an equal amount of glass will be ground from both sides of the lens simultaneously.

Other objects and advantages of the invention will become apparent during the course of the following description.

In the drawings, wherein like numerals are 25 employed to designate like parts throughout the same,

Figure 1 is a top plan of the invention,

Figure 2 is a vertical transverse section taken through one form of the invention, 30 and

Figure 3 is a vertical transverse section taken through a slightly modified form of the invention.

In the drawings, wherein for the purposes 35 of illustration is shown the preferred embodiment of the invention, the numeral 5 designates the drive shaft, which is propelled by means of the belt and pulley connection 6. Keyed to the shaft 5 by means of the key 40 7 is a ball member 8, said shaft 5 passing through a centrally disposed aperture formed in the said ball. The ball member 8 should be of a hardened highly polished material so as to form a good bearing surface.

The stone 9 is carried by the stone clamping means 10, which means has extending 45 therefrom the web 11, which terminates in the semi-spherical or cup shaped ball 12 which has a centrally disposed aperture formed as is shown in Figure 2 of the drawings. The centrally disposed opening 13 is slightly larger than the diameter of the shaft 5 and the face 14 is bevelled to allow for the movement of the cup shaped member 12.

The cup shaped member 12 is of a size to re-

ceive the ball 8 therein, whereby the ball 8 forms a bearing for the cup to rock upon and as the face 14 is bevelled the cup which carries the clamping member 10 and the stone 9, may be rocked sufficiently to allow 60 the stone 9 to accommodate itself to any form of ophthalmic lens. A second cup member or semi-spherical member 15, having the web 16, is clamped to the cup shaped member 12 and the web 11 by the means of 65 the bolts 17.

It will, of course, be understood that the cup member 15 is likewise provided with the centrally disposed aperture 18, while the face 19 is bevelled similar to that of the face 14. 70 The two members thus clamped together form an adequate socket for the polished ball 8.

The drive mechanism for the stone 9 comprises a block 20 which is keyed to the shaft 75 5 by means of the key 21. An arm 22, which may be termed as the driver, has the angular extension 23, which is adapted to be received within a suitable socket formed in the block 20 in such a manner that the said driver 80 will at all times rotate with the block 20 and the shaft 5. A metallic hardened bushing 24 is seated within the web portions 11 and 16, said bushing being provided with an opening so as to allow of the insertion of the driver 22 therethrough. The curved face 25 is provided to allow the bushing, which is carried by the stone mounting, to rock upon the driver in and for the purpose that will 85 be readily understood.

In Figure 3 of the drawings the numeral 26 designates a bearing race-way which is keyed to the drive shaft 6'. A stone 27 is carried by the stone clamping means 28, which comprises the web 29, flange 30 and removable ring 31 which is held in place by means of the bolts 32. The web 29 terminates in the bearing race-way 33, and suitable balls 34 are interposed between the bearing race-ways 26 and 33 respectively. 90 The race-way 33 is arcuated as is shown at 35 to allow the same to rock upon the balls 34, which are seated in the depressions 36.

A block 37 is keyed to the shaft 6' adjacent the race-way 26 and supports the driver 38 similar to the driver 22 in Figure 2. The driver 38 is adapted to be received through the opening 39 formed in the web 29, which opening has the curved surface 40 to allow 105 of a rocking movement of the stone and 110

mounting when in use. A jam nut 41 is screw threadedly mounted by means of the threads 42 upon the shaft 6 to clamp the stone when it is desired to hone or true the stone 27.

It will be seen that I have devised an oscillating or floating stone that will readily accommodate itself to all forms and curvatures of ophthalmic lenses when being ground and that driving means are provided that will ensure rotation of the stone no matter how the stone is rocked upon the shaft 6. In view of the bearing surfaces between the stationary and oscillatory portions of the mounting, it requires but slight pressure to tilt the stone.

It is therefore to be understood that the form of my invention herewith shown and described is to be taken as the preferred embodiment of the same and that various changes in the shape, size and arrangement of parts may be resorted to without departing from the spirit of my invention or the scope of the subjoined claims.

Having thus described my invention, I claim:

1. In a device of the character described, a drive shaft, a member on the driveshaft having a spherical bearing surface, an annular grindstone member having a bevelled groove in its periphery, an annular grindstone holding member comprising means for holding the annular grindstone member, spherical bearing means adapted to cooperate with the bearing member on the shaft

so that the grindstone may be laterally rocked on the bearing member and a transverse orifice having an arcuate bearing surface, and an engaging member secured to the shaft having a projecting portion extending through the orifice in the grindstone holding member and engaging the arcuate bearing surface, whereby the grindstone may be rotated by the movement of the shaft and permitted to rock laterally on the spherical and arcuate bearing surfaces to compensate for lateral displacements of the grindstone caused by the shape of the object which engages the bevelled peripheral groove in the grindstone.

2. In a device of the character described, a shaft, a ball member secured to the shaft and having a bearing surface, a grindstone annulus, a grindstone holding annulus comprising means for holding the grindstone, bearing means to engage the bearing surface of the ball member on the shaft, said annulus having a transverse orifice therethrough having arcuate bearing surfaces and a driving member secured to the shaft having a finger extending through the orifice in the grindstone holding annulus whereby the grindstone may be rotated by the shaft and lateral play of the same allowed through the co-action of the bearing surfaces on the finger and ball members with the arcuate bearing surfaces in the orifice and the bearing means in the grindstone holding annulus respectively.

NELSON M. BAKER.
